(57) **CLAIM**

The ornamental design for a toy brick with ring out connector as shown and described.

DESCRIPTION

FIG. 1 is a first top perspective view of a toy brick with ring out connector.

FIG. 2 is a first side plan view of the toy brick with ring out connector.

FIG. 3 is a second side plan view of the toy brick with ring out connector.

FIG. 4 is a first end plan view of the toy brick with ring out connector.

FIG. 5 is a second end plan view of the toy brick with ring out connector.

FIG. 6 is a top plan view of the toy brick with ring out connector.

FIG. 7 is a bottom plan view of the toy brick with ring out connector.

FIG. 8 is a first bottom perspective view of the toy brick with ring out connector.

FIG. 9 is a second top perspective view of the toy brick with ring out connector.

FIG. 10 is a second bottom perspective view of the toy brick with ring out connector.

FIG. 11 is a front perspective view of a toy brick with ring out connector.

FIG. 12 is a first top perspective view of a second embodiment of the toy brick with ring out connector.

FIG. 13 is a first side plan view of the second embodiment of the toy brick with ring out connector.

FIG. 14 is a second side plan view of the second embodiment of the toy brick with ring out connector.

FIG. 15 is a first end plan view of the second embodiment of the toy brick with ring out connector.

FIG. 16 is a second end plan view of the second embodiment of the toy brick with ring out connector.

FIG. 17 is a top plan view of the second embodiment of the toy brick with ring out connector.

FIG. 18 is a bottom plan view of the second embodiment of the toy brick with ring out connector.

FIG. 19 is a first bottom perspective view of the second embodiment of the toy brick with ring out connector.

FIG. 20 is a second top perspective view of the second embodiment of the toy brick with ring out connector.

FIG. 21 is a second bottom perspective view of the second embodiment of the toy brick with ring out connector; and,

(Continued)

FIG. 22 is a front perspective view of the second embodiment of a toy brick with ring out connector. The broken lines in the figures show features of the toy brick with ring out connector that form no part of the claimed design.
